SHOE-SCRAPING DOOR MAT

Eric Armand Knutsson, Stockholm, Sweden, assignor to Henric Giesecke, Stockholm, Sweden

Application October 3, 1946, Serial No. 700,991
In Sweden September 23, 1946

4 Claims. (Cl. 15—238)

1

This invention relates to improvements in door mats of the type which are used in scraping the soles of shoes, boots, etc.

Mats consisting of laths fastened to two sides of a frame and containing elastic material between the laths, have proved to have a very good wiping capacity. They have a pleasant appearance, and, owing to their elasticity, they are comfortable in use. For these reasons, they have been very popular.

In the known mats of the above type the laths have been rigidly arranged. This resulted in strains in the mats, which sometimes have been so considerable that individual laths in the mats broke under the strain.

The primary object of this invention is to overcome this difficulty and produce a mat in which no such strains occur. According to the invention this is attained by providing parts of the frame, which are intended to be used for fastening the laths, with grooves adapted to receive the ends of the laths, and by inserting the latter in said grooves. In this arrangement, the laths will be movable relative to the frame and the individual laths may be exchanged, if necessary. The period of use of the mat is essentially extended by this arrangement.

In order to more safely fasten the laths, I prefer to make their ends dovetail shaped and the grooves of a shape registering therewith.

The invention will be explained with reference to the annexed drawings. Fig. 1 shows, partly in section, a piece of a mat according to the invention. Fig. 2 shows a section along the line II—II in Fig. 1.

The frame is provided with a groove 2, in which the dovetail shaped ends 3 of the laths 4 and the likewise dovetail shaped end 5 of the other frame-piece 6 are placed. To this piece, as well as to the laths 4, strips 8 of elastic material, e. g. rubber, are fastened by means of fastening means 7. The ends of the frame-pieces are connected with each other by means of screws 9 and 10, and an angle-bar 11.

If it is necessary to exchange a lath for any reason, the two screws 9 in the framework-piece 1 and the corresponding screws at the other end of the frame-piece 6 are removed, whereupon this piece and as many laths 4 as necessary for the removal of the lath to be exchanged, as well as the latter, are removed, whereupon a new lath is inserted and the mat is reassembled.

The assembly, thus described, presents a number of advantages, some of which are indicated above and others are now presented:

2

The frame is a formation readily produced and capable of ready assembly and easily manipulated for purpose of repairs. The end members 1 each have the inner sides formed with the dove-tail groove 2 extending from end to end and thus capable of ready formation; the side members 6 have their ends formed as tenons complementary to and slidable in the grooves; the end and side members have no other direct connection.

10 The anchoring connection between these members is provided by the external angle irons 11 located at the corners of the assembly with the screws 9 securing the iron to the end member and screws 10 securing the iron to the side member. By withdrawing screws 9 at opposite ends of one of the side members, such side member, carrying the freed angle irons, is then readily withdrawable from the groove 2 of the end members, thus completely opening the assembly and 20 a reversal of this regimen permits the frame to be re-assembled.

The interior of the frame is provided by a series of individual units which extend parallel with the side members 6. Each unit includes a rigid element, the lath 4, the ends of which are tenoned similar to the side members for slidable movement in grooves 2, and a resilient element, indicated at 8, which has a width greater than the similar dimensions of the frame members and the rigid member. The resilient element is of elongated type with a length materially greater than the length of the rigid member of the unit, and is secured to a side face of the latter at uniformly spaced points in the length of both elements. The spacing distance between adjacent 30 points of the rigid member is materially less than the spacing distance of the points of the resilient member, thus producing an excess of material of the resilient element between the securing points, such excess taking the form of a corrugation, with the corrugation between adjacent points closed by the face of the rigid element to which the resilient element is secured. The corrugation produced on the opposite side of the

35 resilient element at the securing point is an open corrugation (in the assembly, the latter corrugation is closed by the opposing side of the adjacent unit rigid element). As a result, the resilient element of the unit presents a length configuration of substantially continuous sinuosity, with alternate corrugations closed by the rigid element of the unit and with the intervening corrugations open, and with each corrugation as of material depth.

45 55 The resilient element of the unit is carried

by the same side of the rigid element in successive units with the result that when the series of units is mounted within the frame, the assembly will present a spaced-apart succession of resilient elements having their edges extending above and below the opposite planes of the top and bottom faces of the frame members and the rigid elements, such edges presenting the sinuous formation. Since the corresponding corrugations are alined in parallelism with the frame end members, there is provided an exposed scraping face formed by such edges, while the lower edges provide the surface which contacts the support, as indicated in Fig. 2. While, under the weight of the user, there may be a tendency for the lower edges to yield slightly, the structure is such that the exposed under edges act to prevent creeping of the mat, when the latter is being subjected to scraping use.

Each of the unit rigid members has its end portions formed complementary to the dove-tail groove 2, being free to move longitudinally thereof, the only connection between the rigid element and frame end members being the complementary dove-tail connection. Hence, when side member 6 is removed, the units can be successively located within the grooves 2 through the open end of the latter until the desired number has been introduced, after which the side member 6 is placed in position, with screws 9 then securing the angle irons 11 to the end rails to complete the mat. Obviously, should one of the units become damaged to such an extent as to require removal, the reverse of the above operation is provided, withdrawal of screws 9 permitting the side member 6 to be withdrawn from the grooves 2, after which the units are successively withdrawn until the damaged unit is reached. The latter is then withdrawn, repaired or a substitute unit inserted, after which the withdrawn units are restored and the side member 6 positioned in the manner previously described. As will be understood, the side member 6 is also provided on its inner face with one of the resilient elements 8, the opposite side member 6 does not carry such resilient element, its inner face serving to support the resilient element of the first-entered unit, thus providing uniformity in the mat arrangement.

The dimensions of the mat and of its individual elements are such that when assembled, the structure presents stability and looseness is avoided through the presence of the resilient zones, even though the units are free to move in the grooves. If part dimensions are such as to tend to crowd the assembly by being slightly oversize, no difficulty is provided since pressure applied to the side member 6 will simply cause corrugations of the resilient elements to flatten slightly and in such case the free slidability of the units in the grooves 2 is advantageous since the units are free to adjust themselves to the changed conditions, thus assuring uniformity in the spacing of the scraping edges provided by the upper edges of the resilient elements.

The upper exposed edges of the resilient elements form the scraping edges of the mat, the corrugations being spaced and under more or less tension, provide for efficiency in the scraping action. In such service conditions, the free slidability of the units is not disadvantageous, due to the fact that the user can only scrape one foot at a time as he must support his weight with the other foot. If the scraping action should tend to advance a unit, the scraping pressure would be limited to one end of the unit (the

stationary foot would anchor the other unit end) thus attempting to cant the unit, an action which would be resisted by the complementary portions of the dove-tail action provided by the groove and tenon. In other words, while the unit is free to slide in the grooves when both ends of the unit are moved concurrently, such slidability is prevented when but one end of the unit is subjected to the advancing pressure.

It will be understood from the above description that various modifications of the arrangement shown may be made without departing from the spirit of the invention. The mat shown in the drawing is made of wood with strips of rubber. Instead of wood other suitable materials, for example metals, and instead of rubber, other suitable materials, such as leather, may be used.

It has been found that plastic materials are very suitable for the entire mat, as they have a very attractive appearance. The laths should be made of a harder material than the strips.

What I claim is:

1. A mat construction comprising a rigid frame of rectangular contour, and a plurality of scraping units mounted within said frame and constituting the active scraping surface of said mat, said frame comprising a pair of parallel spaced side members and a pair of parallel spaced end members disposed perpendicularly of said side members, each of said end members having a central longitudinal groove in its inner face, said grooves extending substantially the entire length of said end members, each of said scraping units comprising a rigid rectangular element whose ends are slidably supported in the respective slots of said end members whereby each of said rigid elements is freely slideable in a direction parallel to the longitudinal axis of said end members, each of said scraping units also comprising an elongated compressible and bendable resilient strip whose normal expanded length is materially greater than the length of said rigid element, said resilient strip being secured to a side face of the rigid element at equally spaced-apart points lengthwise of said rigid element, the spacing distance between adjacent securing points on said resilient strip being such as to cause said resilient strip to be sinuously disposed relative to said rigid element, presenting arcuate outwardly-projecting crowns of equal size between each two adjacent securing points, the plurality of scraping units being assembled within said frame with said arcuate crowns of the sinuous contour of one unit in contact with the adjacent face of the adjacent unit to thereby present the active mat surface as formed with spaced sinuous surfaces interposed with rigid elements, said resilient strips yieldably maintaining said rigid elements evenly-spaced and parallel to each other and to said side members.

2. A mat construction according to claim 1 in which the longitudinal grooves of said end members are of dove-tail shaped cross-section, and in which the ends of said rigid elements are formed as tenons complementary to the groove cross-section.

3. A mat construction according to claim 1 in which one of the side members of said frame is removably secured to said end members, whereby upon removal of said side member, the scraping units may be slid out of said frame.

4. A mat construction according to claim 1 in which the height of each resilient element is greater than the height of said rigid elements and said frame, said resilient elements projecting

5

above and below said rigid elements and said frame.
